FIG. 1 is a front view of a folding garage door incorporating the features of my design.

FIG. 2 is an enlarged sectional side view of the folding garage door of FIG. 1, taken on the lines 2—2 of FIG. 1.

FIG. 3 is a fragmentary side view, in section, showing adjacent hinged sections of the folding garage door in a partially opened position of the door.

The broken lines shown in the drawing are for the purpose of background illustration only and form no part of the ornamental design. The rear of the door is plain and unornamented and is provided with conventional hinges.

I claim:

The ornamental design for a folding garage door, as shown and described.
